FIRE EXTINGUISHER

William Koehler, Cleveland Heights, Ohio

Application September 17, 1943, Serial No. 502,782

5 Claims. (Cl. 169—31)

This invention relates to an improvement in fire extinguishing media and means to discharge such media from a storage receptacle. More particularly, this invention relates to a glaze-forming fire-extinguishing medium and a fire extinguisher which will discharge such a medium under the pressure of a fire-extinguishing gas in such a manner that substantially all of the fire-extinguishing gas will be carried with the discharged medium, thereby obtaining the optimum utilization of the fire-extinguishing gas. My invention is useful in extinguishing substantially all types of combustion supported by the ambient atmosphere and is especially useful in extinguishing high-temperature combustion such as that produced by burning metallic magnesium. This application is a continuation-in-part of my application for a fire extinguishing medium, Serial No. 475,697, filed February 12, 1943.

It is the general practice to smother a fire by a blanket of an incombustible medium in the form of a gas, liquid, or powder. When the extinguishing medium is applied in such forms, however, the volume of extinguisher required is dependent not only upon the area to be blanketed but also upon the violence of the fire. In order to reduce the volume of extinguisher required, the extinguisher is often applied in the form of a foam. However, even foams tend to break down and blow away when employed on violent high-temperature fires. It is the object of this invention to provide a fire-extinguishing medium which cannot only be applied in the form of a foam but which also forms a hard glaze or varnish upon the burning surfaces when the foam tends to break down under high temperatures.

It is also general practise to expel a fire-extinguishing liquid from a storage container by means of a fire-extinguishing gas under pressure. A fault of most of such fire extinguishers, however, is that a substantial portion of the gas remains in the container until after the liquid is discharged; thus, a substantial portion of the gas is not utilized as an extinguishing medium but is simply dissipated into the atmosphere. It has been proposed to so baffle the discharge nozzle of a storage container that the expelled liquid and expelling gas will be intermingled into a foam which carries the expelling gas along with the expelled liquid; the increased resistance of such baffles, however, required an increase in static pressure of the gas within the storage containers and thus defeated the purpose of the proposals. Accordingly, it is another object of this invention

to provide a fire extinguisher in which the expelling fire-extinguishing gas is intermingled with a fire-extinguishing liquid to form a foam while minimizing the static gas pressure required for expulsion of the fire-extinguishing liquid.

My means for accomplishing the foregoing objects of my invention, as well as other objects and advantages of my invention, will be apparent from the following specification, claims, and drawing, in which:

The sole figure is a vertical cross-section of a fire-extinguisher made according to my invention.

My fire-extinguishing medium is preferably comprised of a neutralized or alkaline aqueous solution or suspension of an inorganic wetting and glaze-forming agent or agents, such as, for example, an aqueous solution of metallic haloids such as calcium chloride and/or magnesium chloride. Other suitable wetting and glaze-forming agents may be sodium ammonium phosphate, sodium phosphate, borax, and the like.

As a specific example of my fire-extinguishing liquid, approximately equal parts of calcium chloride and magnesium chloride are dissolved in water until the specific gravity of the solution ranges between 1.2 and 1.5. Calcium hydroxide is then added to the solution until the pH value ranges from 7 to 9. The solution is then filtered to remove undissolved calcium hydroxide or allowed to stand until the clear solution can be decanted.

In commercial practice, residue brines or bitters may be employed as the source of magnesium chloride and suitable quantities of calcium chloride may be added, if necessary. Care should be taken to dilute the calcium chloride and magnesium chloride solutions to a specific gravity ranging between approximately 1.2 and 1.5. If the lower limit is not met, the solution will not have effective strength; if the upper limit is exceeded, crystallization is likely to occur during storage at low temperatures. Suitable wetting and glaze-forming agents such as those suggested may be employed but in all cases the solutions should be at least neutralized to avoid corrosion of the storage containers employed.

My fire-extinguishing liquid is preferably stored in a container as disclosed in the drawing in which 10 represents a storage container or vessel provided with a liquid-refill safety plug 12. Threadedly secured in the container 10 is the fitting 14 having the discharge passage 16 leading from the interior of the container 10 to the exterior of the fitting 14. At the exterior port of the passage 16 a discharge nozzle 18 is threadedly secured; the

nozzle 18 may be replaced by the conventional flexible hose and nozzle if desired.

A vertical well-tube 20 is fixed in the fitting 14 at the interior port of the discharge passage, the well-tube extending from the fitting 14 nearly to the bottom of the container 10. A small relief vent 21 is drilled through the tube 20 adjacent the discharge passage. Within the well-tube 20 and concentric therewith is a gas tube 22 carried at one end by the fitting 14, the other end of the gas tube 22 terminating just above the bottom of the container 10. The gas tube 22 is connected to a gas storage cylinder 24 by gas passages 26 in the fitting 14. In the embodiment disclosed the gas cylinder 24 is carried by the fitting within the container 10 to protect the cylinder from rough handling. The gas passages between the cylinder 24 and tube 22 are closable by the normally open plug 27 and the normally closed needle valve 28. A spur passage entering between the plug 27 and the gas cylinder 24 is normally closed by the refill plug 29.

The operation of my fire-extinguisher is as follows: With the container 10 filled with my fire-extinguishing liquid as described above and with a fire-extinguishing gas, i. e., carbon dioxide, sulphur dioxide, ammonia, nitrogen, chlorine, or the like, under pressure in the gas cylinder 24, the normally closed discharge valve 28 is opened as shown in the drawing. Gas is discharged through the passages 26 and gas tube 22 to the bottom of the container 10, where the gas breaks into bubbles and rises in the well-tube 20. In order to decrease the size of the bubbles, the open end of the gas tube 22 may be serrated, as shown. As the gas rises in the well-tube 20, fire-extinguishing liquid is carried with the gas. Due to the dissolved wetting agents in the fire-extinguishing liquid, the surface tension of the liquid is reduced and froth or foam commences to be produced in the well-tube 20. Due to the absence of baffles and a minimum of restriction in the discharge passage 16 and nozzle 18, the gas continues to expand as it rises in the well-tube, thus accelerating the entrained foam. Probably because the acceleration of the foam is due primarily to the expansion of the expelling gas, there is apparently comparatively little back or static pressure in the container 10. In order to maintain within the container a pressure which is at least above atmospheric, the small relief vent 21 in the tube 20 bleeds some pressure from the well-tube to allow the liquid to fall in the container 10; also, if the supply of liquid is not exhausted in the use of the extinguisher, the gas cylinder is closed by the valve 28 and such back pressure as may exist can bleed back into the well-tube without further discharge of liquid. The vent 21 also serves the function of allowing air retained in the container to expand and contract during storage without discharging the liquid.

As the foam of liquid and expelling gas leave the nozzle 18, gas dissolved or absorbed in the liquid during the travel up the well-tube and through the discharge passage will be released, further breaking up the liquid into a gas-liquid emulsion. The discharged stream of gas-liquid emulsion hits the burning surfaces as a wet, sticky foam which breaks down rather quickly, releasing the smothering gas and wetting the surfaces with the fire-extinguishing liquid. If the temperature of the fire is such that it evaporates the water quickly, thus overcoming the wetting action of the liquid, the dissolved agents are precipitated on the wetted surfaces as fine powders

which quickly fuse into a hard, incombustible glaze or varnish which will withstand extremely high temperatures and which will prevent the surfaces from being reignited by sparks, for example.

From the foregoing it should be apparent that my fire-extinguishing liquid is particularly useful in extinguishing high-temperature fires, such as burning magnesium. Normally water and aqueous solutions should be avoided in extinguishing magnesium fires, but my aqueous solution may be used successfully because of the residual glaze produced and because the solution is applied as a foam, thus avoiding the steam explosions which result when streams of liquid are employed.

It should also be apparent that my container may be readily recharged. The container 10 is refilled through the plug 12. To recharge the gas cylinder 24, the plug 27 is closed, the plug 29 is removed, and the fitting 14 is connected to a suitable reservoir of compressed, i. e., liquified, gas. The valve 28 is then opened and the cylinder 24 is recharged. When recharging is complete, the valve 28 is reclosed, the plug 29 is replaced, and the plug 27 reopened. In some instances it may be more convenient to recharge the container with gas by substituting the cylinder 24 with a new sealed gas cylinder. In such instances either the needle valve stem of the valve 28 or the socket for the gas cylinder should be provided with a suitable seal-puncturing projection. It is also to be understood that in certain embodiments the disclosed manual valve 28 may be replaced with a suitable temperature-responsive automatic valve.

From the foregoing, it is apparent that my invention is not limited to the specific and preferred embodiments disclosed but may be modified, either in whole or in part, within the scope of the appended claims.

What is claimed is:

1. A storage container for a fire-extinguishing medium comprising a container having a discharge passage, an open-ended well-tube extending from said discharge passage to a point adjacent the bottom of said container, a first means for introducing gas into said well-tube adjacent the open end thereof, a reservoir for containing gas under pressure, a second means connecting said reservoir to said first means, and a valve in said second means for controlling the flow of gas from said reservoir to said first means.
2. A storage container as defined in claim 1 in which said well-tube is vented to the interior of said container adjacent said discharge passage.
3. In a storage container for a foamable fire-extinguishing liquid, a foam-forming discharge mechanism comprising a vertical open-ended well-tube within said container connected to a discharge passage in said container, the open end of said well-tube extending below the normal level of liquid in said container, a gas tube having an outlet into said well tube adjacent the open end thereof, a reservoir for storing gas under pressure, means having a gas passage for connecting said gas tube to said reservoir, and a valve for controlling the flow of said gas from said reservoir into said well-tube.
4. In a container as defined in claim 3, gas reservoir recharging means comprising a means for closing said gas passage between said valve and said gas tube, and a recharging plug normally closing a spur passage connected to said gas passage between said closing means and said valve.

5. In a device for storing a foamable fire-extinguishing liquid and for discharging such liquid as a foam, said device comprising a liquid container having a discharge opening, a gas reservoir, and a valve for controlling the flow of gas from said reservoir, a liquid discharging and foaming means comprising a vertically extending tube connected to the discharge opening and having a vent adjacent said opening, said tube having an open end below the normal level of 10

liquid stored in the container, and means connected to said valve to introduce gas from the reservoir into said tube adjacent said open end thereof and to cause bubbles to form in said tube when liquid is stored in said container, whereby the bubbles will rise in said vertically extending tube and will discharge in the form of foamable liquid stored in said container.
